UNITED STATES PATENT OFFICE

2,583,924

LEATHER SPLITTING METHOD AND APPARATUS

George R. Baumeister, Boston, Mass., assignor to
Lacene Manufacturing Company, Cambridge,
Mass., a corporation of Massachusetts

Application November 4, 1949, Serial No. 125,586

4 Claims. (Cl. 69—13)

1

This invention relates to an improved method and apparatus for splitting or skiving sheet materials such as leather blanks wherein a pair of vertically adjustable feed rolls are arranged to advance a leather blank against a rigidly held knife blade. One desirable form of the invention is exemplified by use in connection with a splitting machine such as that described in the Nichols Patent No. 1,205,104, issued November 14, 1916. However, it is not intended that the invention be limited in its application to this or any other particular form of leather skiving machine.

In the art of skiving or splitting leather blanks, notwithstanding the many improvements which have been made from time to time, there still remains considerable difficulty with "gouging," i. e. the occurrence of too deep a knife cut in certain localized areas of an evened blank.

Various proposals have been made to overcome this difficulty involving the use of a movable cutting element or knife which when presented to the leather blank can result in a desirable slicing action and an easier cut. A principal objection to these proposals lies in the fact that unless an extremely rigid and hence a massive and expensive support is provided for the knife, there will be some deflection of the knife with respect to the rolls as the load or stress is applied. As much as .003 of an inch deflection is definitely undesirable. In this connection it is found that in older types of splitting machines where the knife is bolted to the bed of the machine, extreme tension on the knife bolts or for example two tons or more is necessary to keep the knife rigidly clamped to the heavy frame casting.

It is in general an object of the invention to deal with the problem indicated and to devise efficient and accurate means of skiving leather blanks without the occurrence of gouging or other undesirable irregularities.

With this objective in mind therefore, I have conceived of a method and means which provides for relative movement between a splitting machine knife and a leather blank in order to provide a uniform cut or slicing action which substantially eliminates gouging. In my improved method, the knife blade is held in a stationary position and the leather blank to be skived is oscillated in a direction transversely of the forward path of movement of the blank as it passes along the machine.

An important feature of the invention is the combination with the skiving knife of a pair of

2

vertically adjustable roll bearings and a pair of oscillatable rolls secured in these bearings in a position to feed a leather blank against the knife, and to simultaneously draw the blank transversely back and forth across the blade, thus developing a slicing action.

These and other objects and novel features will be more fully understood and appreciated from the following description of several preferred embodiments selected for purposes of illustration and shown in the accompanying drawings, in which

Fig. 1 is a view shown partly in cross section and partly in elevation, illustrating a typical skiving machine with which the invention may be utilized;

Fig. 2 is a detail end elevational view of roll mechanism of the invention;

Fig. 3 is a front elevational view of the roll and cam mechanism shown in Fig. 2;

Fig. 4 is a side elevational view of a modified roll mechanism for handling leather blanks;

Fig. 5 is a detail view of cam mechanism disclosed in Fig. 4;

Fig. 6 is a fragmentary elevational view of another modification of skiving roll mechanism of the invention; and

Fig. 7 is a fragmentary elevational view of still another roll modification.

In the structure shown in the drawings, there has been illustrated several of the more common parts of an evened and grading machine of the type described in the Nichols patent above referred to. These portions of the machine serve merely to conveniently illustrate one typical grading machine arrangement with which the invention may be utilized, and include a pair of measuring rolls 10 and 12 of the usual type journaled in bearing members 14 and 16 in turn received in a frame 13. The rolls are adjustably supported in a vertical direction by means of the usual spring elements 20. A chain and conveyor member 22 is arranged to advance a leather blank from the measuring rolls into a skiving position. It is pointed out that the mechanism above described forms no part of the present invention and might, if desired, be eliminated or replaced by a hand feeding operation.

In accordance with the invention, I provide two feed rolls 24 and 26, which are fixed on journals 28 and 30 in turn rotatably mounted in upper and lower roll bearings 32 and 34. Gears 36, 38 and 40 drive the rolls in the usual manner to advance a sheet material such as a leather blank in a direction from right to left as viewed

in Fig. 1 for example. The roll bearings 32 and 34 are supported by means of springs 21 as suggested in Fig. 3 and these bearings are free to move vertically but not laterally in ways in the frame of the machine.

However, unlike previous roll mountings, the rolls 24 and 26 together with their respective journals 28 and 30 are free to move laterally or transversely in the roll bearings 32 and 34. As suggested in Fig. 3, the journals may be elongated to provide for a definite amount of lateral displacement in either direction and similarly the large driving gear 40 may have a width substantially exceeding that of gear 38 so that the latter gear is free to move along gear 40 during the meshing operation.

To carry out the lateral displacement of the rolls referred to, I have provided roll oscillating means as shown at the left-hand side of the bearing members 32 and 34, as viewed in Fig. 3. A pair of cylindrical cams 42 and 44 is fixed on the journals 28 and 30 and formed with helical cam grooves 46 and 48. Extensions 50 and 52 of roll bearings 32 and 34 carry stationary cam follower pins 54 and 56, arranged to project into and follow the grooves 46 and 48 of the cams 42 and 44.

In operation as the gears rotate the rolls 24 and 26, the cams 42 and 44 are in turn rotated and travel laterally of the frame in response to the action of the stationary cam followers 54 and 56. The journals and rolls are thereby caused to move relative to the bearings 32 and 34 transversely with respect to the path of forward movement of a leather blank passing through the rolls.

It is pointed out that the rolls grip the leather blank from two opposite sides and successively hold progressive portions of the blank along two coincident lines of contact so that the parts of the blank which are leaving the nip of the rolls are at all times drawn back and forth across the knife blade edge 60, against which the blank is continually being forced.

There is thus realized a combined drawing and forcing action which serves to slice the leather blank in a highly efficient manner which is capable of substantially eliminating gouging effects. By the mechanism described, uniform slicing action may be carried out with respect to various other types of sheet materials of uneven thicknesses.

If desired, the oscillating or drawing speed may be varied throughout a relatively wide range of speeds although good results have been obtained at relatively slow speeds timed to movement of the rolls themselves. I may also desire to vary the means of producing the oscillating or drawing action as has been noted, for example, in the remaining figures of the drawings of which Figs. 4 and 5 represent a roll oscillating arrangement having an eccentric cam 70 independently driven by gears 72 and 74, the latter of which is mounted on a shaft 76 occurring angularly with respect to the axis of the feed rolls 78 and 80. The latter rolls have journals 86 and 88 slidably mounted as noted above in bearings 82 and 84. Roll 80 is coupled to roll 78 by means of a pair of flanges 90 and 92 fixed at either end of roll 78 as noted in Fig. 4.

The cam 70 rotates against a small roller 94, pinned in a slidable block 96, in turn carried in a frame portion 97, and at the opposite end of the block 96 is nested a ballbearing 98. The ad-

5 jacent extremity of journal 88 is recessed to receive the ball-bearing 98 and is resiliently held thereagainst by means of a spring member 100 secured at the opposite side of the frame between a bearing extension 102 and gear 36.

10 As the cam is rotated, the rolls are oscillated together in the manner already described, with the principal difference that the drive for the cam may be independently operated regardless of whether the gears are turning or not, thus providing for intermittent drawing action if desired.

15 Fig. 6 shows another arrangement for oscillating the lower of two feed rolls 110 and 112 coupled as described above by a flange member 114. In this modification the journal 116 of lower roll 112 is directly connected to an independent reciprocating mechanism comprising a hydraulic system in which a piston 118 is driven by pressure applied alternately from two opposite sides through conduits 120 and 122. It is contemplated that the pressure might be controlled, for example, by a cam, not shown, and operated by a solenoid valve, the cam being turned by the same 20 driving means that turns the roll.

25 Similarly, the modification illustrated in Fig. 7 may be utilized for oscillating the rolls 124 and 126, which are coupled by a flange 128. A reciprocating member 130 is operatively connected 30 to the journal 132 and is driven by a crank arm 134 in turn actuated by an eccentric 136.

35 Various other arrangements and applications of the invention may be resorted to, in keeping with the spirit of the invention as defined by the appended claims.

Having thus described my invention, what I desire to claim and to secure by Letters Patent is:

40 1. An improved leather skiving machine comprising a frame, a skiving knife in the frame, a pair of feed rolls arranged to advance a leather blank against the knife, independently driven means for oscillating one of the rolls in an axial direction, and means for operatively connecting the other roll thereto.

45 2. In a leather skiving machine a frame, a knife element mounted in the frame, roll bearings located adjacent to the knife, a pair of rolls received in the bearings, means for rotating the rolls, journals for the respective rolls being slidably disposed in the bearing members, a collar element secured about one of the journals and extending into engagement with the roll of an adjacent journal thereby to operatively connect the rolls one to the other, a spring member 50 mounted between one of the journals and the frame, and cam means located at an opposite end of the roll for urging said roll against the spring member.

55 3. A device as described in claim 1 in which the oscillating means consists of a crank mechanism.

60 4. A device as described in claim 1 in which the oscillating means consists of a hydraulic mechanism.

65 GEORGE R. BAUMEISTER.
